PERFORATING DEVICE

Leonidas C. Miller, Dallas, Tex., assignor to American Oil Tool Company, Dallas, Tex., a corporation of Texas

Application November 5, 1938, Serial No. 239,015

19 Claims.

(Cl. 164—0.5)

This invention relates to new and useful improvements in perforating devices.

In the drilling of oil wells and the production of flowing wells, it has become common practice to perforate the well casing along its portion which extends through oil bearing sands and it is one object of this invention to provide an improved perforating device for this purpose.

An important object of the invention is to provide an improved perforating device which is adapted to be lowered into a well casing on a wire line or cable and which includes a dry cell or other battery for supplying the electrical current for firing the gun cartridges of the device, whereby the necessity of conducting electrical current from the surface for firing purposes, is eliminated and the running of the tool into the casing, as well as the removal of the same therefrom, is eliminated.

A particular object of the invention is to provide a casing perforator having improved control means for controlling the firing of the cartridges or projections, said control means being so constructed that it may be set at the surface prior to the lowering of the device into the casing and being arranged so that it will automatically fire the cartridges after a predetermined time lapse and in a desired order, in accordance with the setting or adjustment made at the surface.

Another object of the invention is to provide an improved casing perforator including a plurality of gun cartridges for perforating the casing and having means for preventing unintentional or accidental firing of the cartridges during the lowering or raising of the device through the well casing, whereby said cartridges cannot be fired until the device is properly positioned in the desired location.

A further object of the invention is to provide an improved perforator, of the character described, which provides a double switch through which the current must flow to the gun cartridges to fire the same; one of said switches being associated with a mechanical latching means which is arranged to positively prevent closing of said switch during raising or lowering of the device through the well casing.

Still another object of the invention is to provide a time mechanism carried by the device for controlling the firing of the cartridges, whereby said switch may be set at the surface to automatically fire the cartridges at any predetermined time, thereby eliminating the necessity of manually controlling the firing from the surface.

A still further object of the invention is to provide an improved casing perforator which is a self-contained unit and which has its source of electrical power and control switches mounted therein, whereby no connecting or lead-in wires for current or control are necessary, which greatly facilitates handling of the device.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a transverse, vertical, sectional view of the upper portion of an improved casing perforating device, constructed in accordance with the invention,

Figure 2 is a continuation of the parts shown in Figure 1, showing the intermediate portion of the device and illustrating the safety switch and other parts in the position shown as the device is being lowered into the well casing,

Figure 3 is a continuation of the parts shown in Figure 2 and illustrating the lower portion of the device,

Figure 4 is an enlarged, transverse, vertical, sectional view of the intermediate portion of the device and showing the safety switch in a closed position after said device has been properly positioned in the well casing,

Figure 5 is a continuation of the parts shown in Figure 4, with the mechanical latching means in its outward position,

Figure 6 is a transverse, vertical, sectional view, taken on the line 6—6 of Figure 1,

Figure 7 is a transverse, vertical, sectional view, taken on the line 7—7 of Figure 1,

Figure 8 is a horizontal, cross-sectional view, taken on the line 8—8 of Figure 2,

Figure 9 is a horizontal, cross-sectional view, taken on the line 9—9 of Figure 2,

Figure 10 is a horizontal, cross-sectional view, taken on the line 10—10 of Figure 2,

Figure 11 is a horizontal, cross-sectional view, taken on the line 11—11 of Figure 2,

Figure 12 is a transverse, vertical, sectional view showing the latch member in position during the raising of the device through the well casing,

Figure 13 is a wiring diagram illustrating the switch and control means for firing the gun cartridges,

Figure 14 is a view similar to Figure 1 and

illustrating a modified form of control mechanism for firing the cartridges.

Figure 15 is a transverse, vertical, sectional view, taken on the line 15—15 of Figure 14.

Figure 16 is a transverse, vertical, sectional view, taken on the line 16—16 of Figure 14.

Figure 17 is a wiring diagram of the modified form of switch control means, and

Figure 18 is a view partly in elevation and partly in section of the extreme upper portion of the device, illustrated in Figures 14 to 17, with the said upper end connected to ground by means of a removable sleeve.

In the drawings, the numeral 10 designates an elongate tubular section or sleeve which has its upper end provided with internal screw threads. A plug 11 closes the upper end of the sleeve or section 10 and the upper end of this plug has an annular retaining member or cap 12 threaded thereon. A pin 13 projects through an axial opening 12 formed in the cap and an annular shoulder 14, which is formed on the lower end of the pin 13, is confined beneath said cap. The pin 13 is rotatable with relation to the retaining cap 12 and these parts form a swivel connection. The upper end of the pin 13 has the coupling 15 at the lower end of a cable or wire line 15 connected thereto and, with this arrangement, the elongate tubular sleeve or section 10 is suspended from the cable.

The lower end of the section 10 is formed with external screw threads and is connected by means of a coupling collar 16 with a second or lower elongate tubular section 17. A transverse plate or disk 18 is confined between the ends of the sections 10 and 17 (Figure 2), being clamped therebetween and this disk separates the interior of the section 10 from the interior of the section 17. Rotation of the disk 18 is prevented by means of dowel pins 19 which engage in recesses formed in said disk and in the upper end of the lower section 17. The extreme lower end of the lower section 17 is formed with external screw threads which are threaded into the upper end of a housing 20. This housing carries the cartridges 21 which are adapted to be fired to perforate the well casing A, as will be explained.

The details of the housing 20, together with the particular construction of the gun cartridges, forms no part of the present invention and so long as said cartridges are adapted to be fired by means of an electrical current, the purposes of the invention will be carried out. Also, it is pointed out that any desired number of cartridges may be employed.

The sections 10 and 17 form an elongate tubular housing or casing which is separated by the transverse disk or partition 18. This housing is suspended from the cable 15 and since its lower end is attached to the cartridge housing 20, it will be manifest that the latter housing is carried thereby. The cable 15 may thus be utilized to lower the device within the well casing A to a desired position therein.

The upper section 10 is adapted to house a battery for supplying electrical current and is also arranged to receive the operating cams and switches for firing the cartridges, as will be explained. The lower section 17 contains the safety switch and the mechanical latching means which prevents unintentional or accidental operation of the device while the same is being raised or lowered within the well casing A, as will be hereinafter explained. An electrical connecting socket 22 is mounted on the transverse disk or

partition 18 which separates the bore of the upper section 10 from the bore of the lower section 17. This socket is clearly shown in Figure 4 and includes an outer annular, elastic shell 23 which rests upon said disk. Rotation of the shell with relation to the disk is prevented by dowel pins 24, which engage recesses in the lower end of said shell and the top of said disk. The shell is constructed of soft rubber or other elastic, electrical non-conducting material and a socket body 25 is mounted within the upper end of the shell, being molded or otherwise secured therein. The socket body is preferably constructed of Bakelite or similar material and a recess B is formed in the top of said body. A metallic contact sleeve B' is mounted in said recess and serves to conduct an electrical current downwardly through the socket, as will be hereinafter explained. An axial recess C having a contact sleeve C' therein is located in the body and electrical current is also conducted through this sleeve. A plurality of other recesses D are also formed in the body 25 and each recess has a contact sleeve D' similar to the sleeves B' and C'. It is pointed out that the number of recesses D depends upon the number of cartridges contained in the cartridge housing 20, as one of these recesses is provided for each cartridge. The recesses B and C do not lead directly to, or are not directly, connected with, a cartridge but lead through a safety switch, which will be hereinafter explained.

A tubular casing 26 is insertable within the upper section 10 and the lower end of this casing is closed by a plug 27, which is threaded onto its lower end. The plug 27 is hollowed out and has its bottom closed by a disk 28 which is constructed of Bakelite or similar material and which is suitably fastened in the plug. The disk carries a contact prong B² which is adapted to engage within the contact sleeve B' in the recess B when the casing 26 is in position within the section 10. A similar contact prong C² is located axially of the disk 28 and is arranged to engage within the contact sleeve C' of the recess C. A plurality of additional contact prongs D² are also mounted in the disk 28 and are adapted to engage within the contact sleeves D' within the recesses D. With this arrangement, it will be obvious that when the tubular casing 26 is in position within the section 10, the contact prongs B², C² and D² are engaged within their respective contact sleeves so that an electrical connection is set up between said prongs and said sleeves.

The casing 26 extends upwardly substantially throughout the length of the section 10 and said casing is preferably formed in two sections which are connected together by means of a coupling plug 29, said plug being threaded to the two sections of said casing. A switch assembly S, which carries the control mechanism for controlling the firing of the cartridges, as will be hereinafter explained, is mounted within the tubular casing 26 between the plug 29 and the lowermost plug 27. This switch assembly is clearly shown in Figures 1, 6 and 7 and includes a pair of side plates 30 and 30' which are spaced from each other and which extend between the plugs 27 and 29. As is clearly shown in Figure 1, the upper plug 29 is formed with a depending angular lug 31 and the extreme upper ends of the side plates 30 and 30' are suitably fastened to this lug. The lower ends of the plates 30 and 30' are similarly fastened to an upstanding col-

lar or lug 32 which is preferably formed integral with the plug 27. In this manner, the side plates 30 and 30' are rigidly mounted within the tubular casing 26.

Mounted between the side plates 30 and 30' near the upper ends thereof is a timer mechanism T. This mechanism is of standard construction, being actuated by means of a flat spring 33, which spring has one end secured to a shaft 34. The shaft extends through and is journaled within the side plate 30 and has a winding key 35 located on the outer side of the plate 30. A suitable opening 36 is formed in the tubular casing 26, whereby access to the key 35 may be had. The opposite end of the flat spring 33 is fastened by means of a rivet 37 to the inner wall of the side plate 30. A gear train or mechanism is driven by the shaft 34 and this mechanism is such as is used in a watch. The details of the mechanism are not shown since it is of ordinary construction, the mechanism serving to require a predetermined length of time for the shaft to complete one revolution. The mechanism includes a pinion 38 and an enlarged gear 39, which is fastened on a stub shaft 40 which is journaled in the plates 30 and 30' below the spring 33. One end of the shaft 40 extends outwardly through the side plate 30' and has a cam 41 secured thereto. This cam has a recess 42 (Figure 13) formed in its periphery. Obviously, when the spring 33 is wound it is placed under a tension and, as said spring unwinds to return to a normal position, the shaft 34 is rotated to rotate the pinion 38. Rotation of the pinion imparts a rotation to the cam shaft 40 through the medium of the gear train 38 and, therefore, the cam 41 is rotated. The timer T may be constructed so that it will take any given length of time for the cam 41 to complete one revolution, that is, it may take thirty minutes or it may take sixty minutes, depending on how long it takes the gear train to impart sufficient rotation to the shaft 34 to cause the cam shaft 40 to make a complete revolution.

An elongate operating arm or lever is pivoted on a pin 44 on the outer side of the side plate 30'. The upper end of this lever extends contiguous to the periphery of the cam 41 and a lug 45 on said lever is arranged to ride on the surface of said cam, being held in engagement with said cam periphery by a coiled spring 46 (Figure 7). The upper end of the lever 43 is offset and is provided with a roller 47. This roller is arranged to engage a spring switch blade 48, which blade is mounted on an angular bracket 49 secured to the outer surface of the plate 30'. The switch blade 48 is movable between an electrical contact 50 mounted on a bracket 51 secured to the plate, and a second contact 52 which is secured to a second bracket 53. When the lug 45 on the operating lever 43 is riding on the periphery of the cam wheel 41, the switch blade 48 is in engagement with a contact 50. However, when the cam 41 has rotated a complete revolution to move the recess 42 opposite the lug 45, said lug enters the recess, whereby the operating lever 43 is swung on the pivot 44. Such swinging of the lever 43 causes the upper end of said lever to move the switch blade 48 out of engagement with the contact 50 and to engage said blade with the contact 52. The electrical circuits which are closed and opened by the engagement of the blade 48 with the contacts 50 and 52 will be hereinafter described.

The lower end of the operating lever 43 is bent 75

upon itself at substantially a right angle to form a projecting lug 54. When the lug 45 at the upper portion of the lever 43 is riding on the periphery of the cam 41, the lever 43 is in a position, with the lug 54 at its lower end engaging within a recess 55 provided in the periphery of a circular cam disk 56, whereby rotation of the cam disk 56 is prevented. Whenever the lug 45 drops into the recess 42 on the cam 41, the lever 43 is swung, which swinging disengages the lug 54 from the recess 55 in the cam 56 and, when this occurs, the cam 56 is capable of rotation. The cam 56 is mounted on a shaft 57 which is journaled in the side plates 30 and 30', as clearly shown in Figure 1. The cam 56 is located on the outer side of the plate 30', while a gear 58 is fastened on the shaft 57 adjacent the inner side of said plates. The gear 58 is in constant mesh with a gear 59, which latter gear meshes with an operating pinion 60. The pinion 60 is mounted on a shaft 61 which is journaled in the plates 30 and 30' and the outer end of the shaft 61 is provided with a winding key 62 which is located within an opening 63 formed in the outer tubular casing 26. A flat spring 64 has one end secured to the shaft 61 with its opposite end fastened by means of a rivet 65 to the inside of the plate 30. The winding key 62 is utilized to rotate the shaft in a direction to wind the spring 64 and place the same under a tension. The shaft 61 is connected with the cam 56 through the gears 58 and 59 and the pinion 60 and when the spring 64 is placed under a tension, the recess 55 in the cam 56 is opposite the lug 54 on the operating lever 43, whereby said lug may engage within said recess to prevent rotation of said cam. When rotation of the cam is prevented, rotation of the shaft 61 is also prevented and, therefore the spring 64 cannot unwind until the lug 54 is disengaged from the recess 55 to permit rotation of the cam 56.

Since the cam 56 is mounted on the shaft 57, it will be manifest that said shaft is rotated when the cam disk 56 is rotated. The shaft 57 extends through the plates 30 and 30' and has a switch arm 66 keyed or otherwise secured thereto, whereby when the shaft 57 is rotated the switch arm 66 is also rotated. A contact 67 is secured to the outer end of the arm 66 and is arranged to travel over a plurality of contacts 68 which are mounted in a commutator disk 69 which is suitably mounted within the side plate 30. With this arrangement, it will be manifest that when the switch arm is rotated it will successively engage the contacts 68 on the commutator disk as it completes one revolution. The contacts 68 are connected to the cartridges 21 located in the cartridge housing 20 and when engaged by the switch arm contact 67 close an electrical circuit to said cartridges to fire the same, as will be hereinafter explained.

From the foregoing, it will be seen that the timing switch T may be wound and properly set to rotate the cam 41 at a desired speed, whereby a predetermined lapse of time will be necessary for the cam to complete one revolution or a portion of a revolution and move the recess 42 thereof opposite the lug 45 of the operating lever 43. The cam may, of course, be adjusted to so locate the recess 42 that one revolution, or any portion thereof, is necessary to move said recess opposite the lug. During the time that the cam 41 is rotating, the lug 54 at the lower end of the lever 43 is engaged within the recess 55 of the cam disk 56, whereby rotation of the shaft 57 and

switch arm 66 is prevented. When the cam 41 has rotated sufficiently to move the recess 42 opposite the lug 45 on the operating lever, said lug drops into the recess so as to swing the lever 43. Such swinging of the lever disengages the lug 54 from the cam 56 and when this occurs, the spring 64 unwinds to rotate the shaft 57 through the medium of the gears 58 and 59 and the pinion 60. The rotation of the shaft 57 causes the switch arm 66 on said shaft to rotate, whereby the contact 67 on the outer end of said arm passes over and engages the various contacts 68 on the commutator disk 69. As the switch arm completes its revolution, the engagement of the contact 67 with the contacts 68 completes an electrical circuit to the various cartridges 21 so as to fire the same. In this manner, the disk 56 acts as a locking means which prevents operation of the switch arm 66 until such time as the cam disk 41 of the timing mechanism T completes its revolution. Thus, it is possible to accurately control the exact time at which the cartridges 21 are fired.

For supplying the electrical current necessary to fire the cartridges, a dry cell battery 70 of any desired construction is mounted in the upper end of the casing 26 above the plug 29 (Figure 1). This battery is cylindrical in cross-section and is located within an elongated sleeve 71 which has its lower end secured by screw threads to the upper portion of the plug 29. An annular insulating jacket 72 is interposed between the battery 70 and the sleeve 71 and serves to insulate said battery from the sleeve. The lower end of the battery is supported on a coiled spring 73 which is confined within the jacket 72 and the contact 70' at the lower end of said battery engages the spring. A contact screw 74 extends through an axial bore formed in the plug 29 and the upper end of this screw carries a plate 75 which is engaged by the spring 73. With this arrangement, the current may flow from the contact 70' of the battery through the spring and to the elongate contact screw 74. The screw is suitably insulated from the plug 29 by means of an insulating sleeve 76. The lower end of the contact screw is connected by means of a wire 74a with the contact 52 which is mounted at one side of the side plate 30'.

The upper end of the sleeve 71 wherein the battery 70 is mounted, is closed by a cap 77, which cap has an annular insulating collar 78 mounted therein. A contact pin 79 is mounted axially of the insulating collar 78 and has its lower end engaging the contact 70a at the upper end of the battery 70, whereby an electrical connection is established therebetween. The upper end of the contact screw 79 is engaged by a spring pressed plunger 80 which is mounted axially in the lower portion of the plug 11, which closes the upper end of the section 10. The plunger 80 is metallic and, of course, contacts the metallic plug, whereby the same is grounded and, thus, the contact 70a at the upper end of the battery 70 is connected to ground through the screw 79 and the plunger 80. The upper portion of the sleeve 71 which carries the battery 70 is axially aligned within the upper end of the casing 26 by means of a spacing collar 81 which is threaded into said casing. A suitable flanged cap 82 surrounds the extended or projecting portion of the sleeve 71 and overlies the spacing collar 81 and the upper end of the casing 26. The cap is constructed of rubber, or other shock absorbing material and the outer surface of the flanged cap 75

contacts the bore of the section 10, whereby the casing 26 is held in axial alignment at its upper end within said section.

From the above, it will be seen that the battery 70 is carried in the upper portion of the casing 26, while the control mechanism for firing the cartridges 21 is carried in the lower portion of the casing. The upper contact 70a of the battery 70 is connected to ground through the screw 79 and the plunger 80, while the lower contact 70' of the battery is connected through the screw 74 and the wire 74a to the contact 52 which is located on the side plate 30'. As has been explained, the operating lever 43 controls the movement or swinging of the switch blade 48 and, normally, said switch blade is riding on the periphery of the cam 41, whereby said switch blade is out of engagement with the contact 52 and in engagement with the contact 50. When engaging the contact 50, it is obvious that the switch blade 48 has opened the circuit from the battery 70 and therefore no current is flowing from said battery. When the timing mechanism T has rotated the cam disk 41 sufficiently to move the recess 42 opposite the lug 45 of the operating lever, said operating lever swings to the position shown in Figure 7, whereby the switch blade is engaged with the contact 52. When this occurs, the current from the battery 70 may flow to the switch blade 48. From the switch blade the current flows through a wire 48a downwardly to the contact prong B' which is engaged with the contact sleeve B' in the recess B, which is located in the contact socket body 25 at the lower end of the section 10. In this manner, the current from the battery is conducted to the sleeve B' when the switch blade 48 is engaging the contact 52. The current is conducted from the sleeve B' by a wire 48b which has its upper end electrically connected to said sleeve. This wire extends downwardly through an opening 84 which is formed in the transverse partition 18 and has its lower end connected to the flexible switch blade 85 of a safety switch assembly E.

The safety switch assembly E includes an annular body 86 which is suitably fastened within the section 10 near the upper portion thereof. The body 86 has an axial bore 87 which has its upper end closed by an insulating disk 88 which is suitably fastened within the upper portion thereof. The lower end of the bore of the body is closed by a disk 89 which is threaded thereinto. The resilient switch blade 85 has its upper end bolted to the insulating member 88 and the lower end of the lead wire 48b is electrically connected to this upper end. Diametrically opposite the switch blade 85 is a second switch blade 85', similar in construction to the blade 85. The upper portion of the blade 85' is also secured to the disk 88 and a lead wire 85a has its lower end electrically connected with said blade. The upper end of the wire 85a extends through an opening 84' which is located axially in the partition or plate 18 and the extreme upper end of the wire 85a is electrically connected with the sleeve C' which is located in the recess C of the electrical socket 25. In this manner, the switch blade 85' is electrically connected with the prong C' which engages the sleeve C' and a wire 85b leads from said prong to the switch arm 66 which travels over the commutator disk 69.

With the above arrangement, it will be seen that the electrical current is conducted from the battery through the contact 52 and the switch

blade 48, then through the wire 48a downwardly through the prong B² and the sleeve B', then through the wire 48b to the switch blade 85. When an electrical connection is established between the switch blade 85 and the other switch blade 85', as will be explained, the current flows upwardly through the wire 85a, contact sleeve C', prong C² and wire 85b to the switch arm 66. Thus, the current is conducted to the contact member 61 on said switch arm and as said arm engages the contact 68 of the commutator disk 69, the current is carried to the latter contact 68. A wire 68a leads from each contact 68 and extends downwardly to one of the contact prongs D² which is in engagement with one of the sleeves D' located in each recess D in the connecting socket 25. Each contact sleeve D' has the upper end of a lead wire 68b connected thereto and this wire extends downwardly through an opening 84a in the partition 18. The lower end of the wire 68b is connected to one of the gun cartridges 21. Thus, when the switch arm 66 engages the contact 68 on the commutator disk, the current flows from the contact 68 downwardly through the wire 68a, contact prong D², contact sleeve D' and wire 68b to the cartridge connected with said wire 68b. For housing the wires leading from the contact sleeves D', a suitable conduit 90 is located at one side of the section 17 within the interior thereof (Figures 3 and 4). For packing off around the wires 48b, 85a and 68b, which extend through the partition 18, a suitable packing member 91 may be secured to the underside of said partition, being held in place by a retaining ring 92. The packing member 91 has upwardly extending sleeves 91' which extend into the openings in the partition and surround the wires so as to assure a seal around said wires. The provision of the packing element 91 prevents any fluid which might be in the section 17 from entering the connecting socket 25.

From the above, it will be seen that when the timing mechanism T has rotated the cam disk 41 sufficiently to swing the lever 43 so as to close the circuit between the switch blade 48 and the contact 52, electrical current is conducted downwardly from the battery to the blade 85 of the safety switch E. When said switch blade 85 has electrical connection with the switch blade 85', the current is then conducted to the switch arm 66 which travels over the commutator disk 69. At the same time that the lever 43 has moved the switch blade 48 into engagement with the contact 52, the lug 54 at the lower end of said lever has been disengaged from the cam disk 56, which permits the switch arm 66 to rotate around the commutator 69, as has been explained. Therefore, when the current is conducted to the switch blade 85, the switch arm 66 is rotated around the commutator disk to engage the various contacts 68 for firing cartridges. Of course, if there is no electrical connection between the switch blade 85 and the switch blade 85' of the safety switch E, it is impossible for the cartridge to be fired for, obviously, no current can be conducted to the switch arm 66 of the commutator.

For controlling the making and breaking of an electrical connection between the switch blades 85 and 85' an elongate operating rod 93 is disposed axially within the lower section 17 of the housing. The upper portion of this stem extends through an axial opening 89' in the plug which closes the bore of the body 86 of the safety switch E, while the extreme upper end of said stem projects through an opening 88' in the insulating

- disk 88 which closes the upper end of said body. An insulating sleeve 94 surrounds the upper portion of the rod 93 and insulates the rod from the metallic body of the switch. The extreme upper end of the rod 93 is movable within a guide sleeve 95 which extends upwardly from the insulating disk 88. A collapsible bellows 96 has its lower end secured to the upper end of the body 86 and this bellows completely encloses the guide sleeve 95. The upper end of the bellows is closed by a suitable plate 97 which has the wires 48b and 85a extending therethrough. The space around the wires extending through the plate 97 is packed off by packing collars 97'. 10 Confined within the bore 87 of the body 86 and surrounding the insulating sleeve 94 on the rod 93 is a metallic contact ring 98. This ring is movable between the switch blades 85 and 85' and is adapted to be engaged by the offset lower ends of said switch blades. However, when the rod 93 is moved upwardly within the housing, the contact ring 98 is arranged to be moved upwardly beyond the offset lower ends of the switch blades 85 and 85', as shown in Figure 2, whereby said offset lower ends engage the insulating sleeve 94 and are disengaged from said contact ring. In this position, the circuit between the blades 85 and 85' is open and there is no current flowing between said blades. When the operating rod 93 is moved downwardly to the position shown in Figure 4, the contact ring 98 moves between the offset lower ends of the blades 85 and 85' and since it is constructed of metal, serves to close the electrical circuit between said blades. Therefore, when the rod 93 is in the position shown in Figure 2, the switch formed by the blades 85 and 85' is open and it is impossible to fire the cartridges; however, downward movement of the rod moves the ring 98 between the switch blades to close the circuit therebetween.

The switch blades are adapted to operate within an oil bath and to retain said oil within the bore 87 of the body 86, a second collapsible bellows 99 has its upper end secured to the closure disk 89 which is threaded into the lower end of the body 86. The lower end of the bellows is secured to a flanged collar 100 which is confined between and external shoulder 101 and the lower end of the insulating sleeve 94. With such arrangement the movement of the rod axially of the body 86 causes the lower bellows to be expanded or contracted in accordance with such movement. Thus, the oil or other fluid which is within the bellows 99, body 86 and upper bellows 96 is retained in place and the switch blades 85 and 85' operate at all times within such fluid.

The lower end of the operating rod 93 extends through a partition 102 which is mounted in a fixed position within the section 17, being fastened therein by means of screw 103 (Figure 10). The extreme lower end of the rod 93 is fastened to a plate 104 which is slidably mounted within the bore of the section 17. The plate 104 is disposed opposite or in horizontal alignment with a plurality of vertical slots 105 which are formed in the wall of the section 17. A collar 106 surrounds the section 17 on the outer side of said slots and said ring is fastened to the slideable plate 104 by means of screws 107. Manifestly, the ring 106, plate 104 and the rod 93 fastened thereto are slideable vertically with relation to the section 17, such movement being limited by the length of the slots 105. A coiled spring 108 which surrounds the section 17 has its upper end engaging the un-

derside of the collar 106, while its lower end rests on a fixed ring 109 suitably fastened to the exterior of the section by screws 110. The coiled spring 108 constantly exerts its pressure to urge the collar 106 and the plate 104 upwardly, whereby the same are held in their uppermost positions at the upper end of the slots 105.

A latch member 111 is located within the bore of the section and extends through a vertical slot 112 provided in the stationary partition 102. A pivot pin 113 which extends transversely of the slot 112 also extends through the latch member 111, whereby said member is pivotally mounted in the partition. The upper portion 15 of the latch member 111 is arranged to swing outwardly through an elongate opening 114 which is formed in the wall of the section 17. The lower end of the latch member 111 is tapered or reduced and is normally confined behind a retaining lug 115 which extends upwardly from the slideable plate 104. A flat spring 116, which is secured to the latch member 111, engages the inner wall of the section 17 and constantly urges the lower end of the latch member inwardly, whereby the upper end of said latch member is urged outwardly through the slot 114. The engagement of the lug 115 with the lower end of the latch member prevents such swinging of the member and holds the same normally in a position as shown in Figure 2.

For sliding the collar 106 and the plate 104 downwardly in the slots 105 under tension of the spring 108, whereby the operating rod 93 may be moved downwardly from the position shown in Figure 2, a friction carriage 117 is provided, being slideable on the exterior of the section 17. This carriage includes a pair of spaced collars 118 which are connected by friction springs 119. The friction springs are constructed of a spring metal and are bowed outwardly, whereby they engage the bore of the well casing A. The friction spring carriage is arranged to engage the upper end of the collar 106 to force the same downwardly and thereby move the rod 93 downwardly so that an electrical connection between the switch blades 85 and 85' may be established, as will now be explained.

In operation, the timing mechanism T is set for a predetermined time, whereby such predetermined time is required to move the recess 42 of the cam 41 of said mechanism opposite the lug 45 of the operating lever 43. For example, if it is estimated that it will require thirty minutes to lower the device to a desired position in the well casing, then the timing mechanism is set for thirty-five or forty minutes whereby it will require thirty-five or forty minutes for the recess 42 of the cam 41 to move opposite the lug 45 of the operating lever and, therefore, the lever 43 is held in the position allowing the switch blade 48 to engage the contact 50 until such time has elapsed. When the switch blade 48 is engaging the contact 50, the battery 70 is grounded at only one terminal, as is clearly shown in Figure 13. At this time, the latch member 111 within the section 17 is in a retracted position as shown in Figure 2, being held in such position by the lug 115 on the plate 104, which plate is in its uppermost position and is retained in such position by the coiled spring 108. Since the plate 104 is in its uppermost position, the rod 93 which controls the safety switch E is raised, whereby the contact ring 98

is disengaged from the offset lower ends of the safety switch blades 85 and 85'. Thus, there is no electrical connection between the blades 85 and 85' and it is impossible to conduct any current to the cartridges 21 since such current must flow through said blades. With such arrangement, the device may be lowered into the well and there is no danger of prematurely or accidentally firing the cartridges 21.

As the device is lowered into the well, the friction spring carriage 117 rides upwardly on the lower section 17 of the housing, assuming the position shown in Figure 2. The parts remain in this position during the lowering operation and when the desired point, at which the device is to be set, is reached, lowering thereof is halted. The cable 15 is then pulled upwardly whereby the entire device is raised through the friction carriage 117 which remains stationary due to the contact of its springs 119 with the wall of the casing A. Upward movement of the device is continued until the collar 106 strikes the lower end of the friction carriage 117 and when said collar engages said carriage a continued upward movement on the device will cause the collar 106 to be moved downwardly under tension of the spring 108 which is compressed. It is pointed out that the springs 119 of the carriage are stronger than the spring 108, whereby said carriage will remain stationary while the spring 108 is compressed to move the collar 106 downwardly. Since the plate 104 is secured to the collar 106, said plate will move downwardly therewith, whereby the retaining lug 115 on said plate moves away from the lower end of the latch member 111. As soon as said lug disengages this lower end, the latch member swings outwardly under tension of the spring 116 to the position shown in Figure 5, whereby its upper end moves radially outwardly through the opening 114 in the wall of the section 17. The downward movement of the plate 104 not only releases the latch member 111, but also moves the operating rod 93 downwardly, whereby the contact ring 98 is moved into engagement with the switch blades 85 and 85' of the safety switch E so as to make an electrical connection therebetween. When this occurs, the electrical circuit to the commutator which controls the firing of the cartridges is made ready, whereby when the switch blade 48 which is controlled by the timing mechanism T is engaged with the contact 52, the cartridges will be fired.

After the switch blades 85 and 85' of the safety switch E have been electrically connected by the contact ring, the device is in its proper position in the well casing and the cartridges 21 are ready to be fired. At this time, the operating lever 43 has its lug riding on the periphery of the cam disk 41, whereby the switch blade 48 is engaging the contact 50. The device is held in this position until the cam 41 has rotated sufficiently for the lug 45 on the operating lever to move or drop into the recess 42. At this time, the operating lever swings to swing the blade 48 into engagement with the contact 52. Such engagement of the blade 48 and the contact 52 conducts the electrical current from the battery 70 through the wire 74a, then through the contact 52 and the blade 48, then through the wire 48a, contact prong B², contact sleeve B' and wire 48b to the switch blade 85. From the blade 85, the current flows through the contact ring 98, blade 85', wire 85a, contact

sleeve C', prong C², and finally through the wire 85b to the switch arm 66 of the commutator.

At the same time that the operating lever 43 was swung to close the circuit between the switch blade 48 and the contact 52, the lower end of the lever was disengaged from the recess 55 of the retaining cam disk 56 of the commutator switch arm and, therefore, as soon as the circuit is closed to the switch arm, said switch arm begins its rotation around the commutator disk 69. Such rotation of the arm causes its contact 67 to successively engage the contacts 68 so as to make an electrical circuit through the wire 68a, contact prong D² and contact sleeve D' and then through the wire 68b to the respective cartridges 21, whereby the same are fired. By connecting the desired cartridges 21 with predetermined contacts 68 on the disk 69, it is possible to fire the cartridges in any desired order.

When it is desired to remove the device from the well, the housing is lowered with relation to the friction spring carriage until the latch member 111 is below said carriage. As soon as the carriage 117 moves upwardly beyond the latch member, said latch member assumes the position shown in Figure 12, that is, its upper end engages the underside of said carriage. It is then possible to lift upwardly on the cable to remove the entire device from the well casing and the engagement of the latch member with the carriage, moves said carriage upwardly therewith. The engagement of said latch member with the carriage prevents the spring carriage from moving downwardly into engagement with the collar 106, whereby the spring 108 holds the collar and the plate 104 attached thereto in its uppermost position during the lifting of the device. This maintains the operating rod 93 in its raised position, whereby there is no electrical connection between the switch blades 85 and 85' of the safety switch. Thus, by means of the latch member 111 and its particular arrangement, accidental or unintentional firing of any of the cartridges which may remain unfired, is prevented during the raising of the device through the well casing.

After the device is removed from the well, the timing mechanism T, as well as the operating spring 64, and operating lever 43 are re-set, after which the device may again be lowered to a desired position in the well casing. It is pointed out that the device is relatively simple in construction and may be readily assembled or disassembled. When it is desired to replace the battery 70, it is only necessary to remove the plug 11 and lift the entire casing 26 out of the upper section 10. Such lifting is made possible because of the contact prongs which engage with in the electrical receiving socket 25.

In Figures 14 to 18, a slightly modified form of the invention is shown. In this form, the timing mechanism T is eliminated and a solenoid 120 is substituted therefor. This solenoid is mounted on the inside of the side plate 30, being bolted or otherwise fastened thereto. In this construction, the upper contact 10a of the battery is not directly grounded as is shown in Figure 1. Instead the spring pressed plunger 80 has a wire 80a leading upwardly therefrom and this wire extends through a conical connecting member 121 which is threaded onto the upper end of the plug 11. The upper end of the wire has electrical connection with an annular contact ring 122 which surrounds and is insulated from an upwardly extending shank 123 which is made

integral with the connecting member 121. A second contact ring 124 is spaced from the ring 122 and is threaded onto the upper end of the shank, whereby this ring is grounded. With this arrangement, the upper end of the battery is not connected to ground during the lowering of the device into the well.

The other end 70' of the battery is connected by means of a wire 70b which leads directly to the spring arm 85 of the safety switch E, the switch blade 48 and the contacts 50 and 52 of the first form, being eliminated. In this manner, when a ground is set up on the upper end of the battery, a circuit is completed directly to the safety switch E.

For connecting the upper side of the battery 10 to ground, an elongate sleeve member 125 is arranged to be dropped downwardly on the cable 15. This sleeve member is provided with a pair of flexible contact members 126 at its lower end, which are adapted to engage the lower contact ring 122. The sleeve has a second set of contact members 127 which are arranged to contact the upper contact ring 124. When the sleeve 125 is dropped downwardly on the cable 15 and encloses the contact rings as shown in Figure 18, an electrical connection is established between the ring 122 and the ring 124. Since the latter ring is grounded, such electrical connection will cause ground to be connected to the ring 122 and then through the wire 80a to the upper side of the battery 70. The current flows from the battery through the wire 70b to the switch blade 85 of the safety switch E. When the operating rod 93 of the device is moved downwardly, as has been explained, to connect the switch blade 85 with the blade 85' of the safety switch, the current will flow from said blade 85' through the wire 85a and to the switch arm 66 of the commutator. In this form, the commutator disk is provided with an additional contact 68, on which contact the contact member 67 of the switch arm 66 normally rests. Therefore, as soon as the circuit is closed between the blades 85 and 85', a flow of current 45 is directed to the contact 68' because the switch arm 66 is resting on this contact.

The contact 68' is connected by means of a wire 128a to the solenoid 120, whereby said solenoid is energized when the safety switch is closed. Energization of the solenoid 120 attracts an operating lever 43' which is similar in construction to the lever 43. As the lever 43' (Figure 17) moves inwardly toward the solenoid 120, its upper end is engaged beneath a latch member 128, which latch member is constructed of a spring steel or other flexible material. After so engaged, the lever is held in this position against the tension of a coiled spring 46' which is connected to the lower end of said lever. The extreme lower end of the lever 43' has the lug 54 thereon which is adapted to engage the recess 55 in the disk 56 of the commutator operating mechanism.

From the above, it will be seen that when the sleeve 125 is dropped downwardly on the cable, one side of the battery 70 is grounded. The opposite side is directly connected to the safety switch E and when said switch is closed, the current flows through the switch arm 66 of the commutator and the contact 68' to energize the solenoid 120. As soon as this occurs, the operating lever 43' is swung to disengage its lug 54 from the cam disk 56, whereby said disk allows the switch arm 66 to be rotated by means of the operating spring 64, as has been explained. The solenoid, after being energized, is of course de-

energized as soon as the switch arm 66 moves off of the contact 68'. However, since the operating lever 43' has moved beneath the spring latch 128, said lever remains in this position until manually disengaged from said latch. The remainder of the operation of this form of the invention is exactly the same as the first form, hereinbefore described.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A perforating device for a well casing including, a housing adapted to be lowered into said casing on a flexible line, gun cartridges mounted in the casing and arranged to be electrically fired to perforate the casing, a source of electrical current supply within the housing, a timing mechanism within the housing and control means comprising a spring actuated member associated with a timing mechanism within the housing for controlling the flow of current from the source to the cartridges to fire the same.

2. A perforating device for a well casing including, a housing adapted to be lowered into said casing on a flexible line, gun cartridges mounted in the casing and arranged to be electrically fired to perforate the casing, a source of electrical current supply within the housing, and rotatable spring actuated control means within the housing for controlling the flow of current from the source to the cartridges to fire the same.

3. A perforating device for a well casing including, a housing adapted to be lowered into said casing on a flexible line, gun cartridges mounted in the casing and arranged to be electrically fired to perforate the casing, a source of electrical current supply within the housing, control means electrically connected to the source of supply and to the cartridges for controlling the flow of current to the cartridges, and means within the housing and associated with said control means and connected in the electrical circuit of the control means for preventing accidental or unintentional operation of the same, said last named means being operated to permit flow of current to the control means upon an upward movement of the device within the well casing.

4. A perforating device for a well casing including, a housing adapted to be lowered into said casing on a flexible line, gun cartridges mounted in the casing and arranged to be electrically fired to perforate the casing, a source of electrical current supply within the housing, control means electrically connected to the source of supply and to the cartridges for controlling the flow of current to the cartridges, a safety switch connected in the electrical circuit between the source of current supply and the control means for preventing flow of current to the control means prior to the positioning of the device in the well casing, and means actuated by an upward movement of the housing within the well casing for moving the safety switch to a closed position to permit a flow of current to the control means, whereby said safety switch may be closed at any desired elevation of the device within the well casing.

5. A perforating device for a well casing including, a housing adapted to be lowered into

said casing on a flexible line, gun cartridges mounted in the casing and arranged to be electrically fired to perforate the casing, a source of electrical current supply within the housing, 5 means for electrically connecting the source of current supply to the cartridges, a control means interposed in the circuit between the supply and the cartridges for controlling the flow of current to said cartridges, an operating lever associated with the control means and normally preventing operation thereof, and means for actuating the lever to release the control means and permit the same to close the circuit to the cartridges.

6. A perforating device for a well casing including, a housing adapted to be lowered into said casing on a flexible line, gun cartridges mounted in the casing and arranged to be electrically fired to perforate the casing, a source of electrical current supply within the housing, means for electrically connecting the source of current supply to the cartridges, a control means interposed in the circuit between the supply and the cartridges for controlling the flow of current to said cartridges, an operating lever associated with the control means and normally preventing operation thereof, and a timing mechanism within the housing for actuating the lever at a predetermined time, whereby said lever releases the control means to permit the same to operate and close the circuit to the cartridges.

7. A perforating device for a well casing including, a housing adapted to be lowered into said casing on a flexible line, gun cartridges mounted in the casing and arranged to be electrically fired to perforate the casing, a source of electrical current supply within the housing, a spring actuated commutator connected in the electrical circuit between the source of current supply and the cartridges for controlling the flow of current to said cartridges, and means associated with said commutator for normally preventing operation thereof, a timing mechanism for actuating said last named means to release said commutator when desired to permit operation of the commutator, whereby the circuit to the cartridges is closed.

8. A perforating device for a well casing including, a housing adapted to be lowered into said casing on a flexible line, gun cartridges mounted in the casing and arranged to be electrically fired to perforate the casing, a source of electrical current supply within the housing, a spring actuated commutator connected in the electrical circuit between the source of current supply and the cartridges for controlling the flow of current to said cartridges, means associated with said commutator for normally preventing operation thereof, a timing mechanism for actuating said last named means to release said commutator when desired to permit operation of the commutator, whereby the circuit to the cartridges is closed, and a safety switch connected in the electrical circuit between the source of current supply and the commutator and arranged to be closed when the device is properly positioned in the well casing, whereby current cannot flow to the commutator and cartridges until said device is in its desired position.

9. A perforating device for a well casing including, a housing adapted to be lowered into said casing on a flexible line, gun cartridges mounted in the casing and arranged to be electrically fired to perforate the casing, a source of electrical current supply within the housing, a spring actuated commutator connected in the

electrical circuit between the source of current supply and the cartridges for controlling the flow of current to said cartridges, means associated with said commutator for normally preventing operation thereof, a timing mechanism for actuating said last named means to release said commutator when desired to permit operation of the commutator, whereby the circuit to the cartridges is closed, a safety switch connected in the electrical circuit between the source of current supply and the commutator and arranged to be closed when the device is properly positioned in the well casing, whereby current cannot flow to the commutator and cartridges until said device is in its desired position, and means carried by the housing for preventing closure of the safety switch when the device is being removed from the well, whereby unintentional firing of the cartridges during such removal is prevented.

10. A perforating device for a well casing including, a housing adapted to be lowered into said casing on a flexible line, gun cartridges mounted in the casing and arranged to be electrically fired to perforate the casing, a source of electrical current supply within the housing, a spring actuated commutator connected in the electrical circuit between the source of current supply and the cartridges for controlling the flow of current to said cartridges, means associated with said commutator for normally preventing operation thereof, means within the housing for actuating said last named means, to release said commutator when desired to permit operation of the commutator, whereby the circuit to the cartridges is closed, a safety switch connected in the electrical circuit between the source of current supply and the commutator and arranged to be closed when the device is properly positioned in the well casing, whereby current cannot flow to the commutator and cartridges until said device is in its desired position, a friction spring carriage slideable on the housing and associated with the safety switch for closing said switch at the desired time, and a pivoted latch on the housing adapted to lock the carriage against downward movement on the housing and thereby prevent closing of the safety switch during removal of the device from the well casing.

11. A perforating device for a well casing including, a housing adapted to be lowered into said casing on a flexible line, gun cartridges mounted in the casing and arranged to be electrically fired to perforate the casing, a source of electrical current supply within the housing, control means electrically connected to the source of supply and to the cartridges for controlling the flow of current to the cartridges, means for actuating the control means at a predetermined time, a safety switch connected in the electrical circuit between the source of current supply and the control means for preventing flow of current to the control means prior to the positioning of the device in the well casing, and means carried by the housing and co-acting with the safety switch for preventing closure of the safety switch when the device is being removed from the well, whereby unintentional firing of the cartridges during such removal is prevented.

12. A perforating device for a well casing including, a housing adapted to be lowered into said casing on a flexible line, gun cartridges mounted in the casing and arranged to be elec-

trically fired to perforate the casing, a source of electrical current supply within the housing, means for electrically connecting the source of current supply to the cartridges, a control means interposed in the circuit between the supply and the cartridges for controlling the flow of current to said cartridges, an operating lever associated with the control means and normally preventing operation thereof, a timing mechanism within the housing for actuating the lever at a predetermined time, whereby said lever releases the control means to permit the same to operate and close the circuit to the cartridges, and a safety switch connected in the electrical circuit between the source of current supply and the control means for preventing flow of current to the control means prior to the positioning of the device in the well casing.

13. A perforating device for a well casing including, a housing adapted to be lowered into said casing on a flexible line, gun cartridges mounted in the casing and arranged to be electrically fired to perforate the casing, a source of electrical current supply within the housing, a spring actuated commutator connected in the electrical circuit between the source of current supply and the cartridges for controlling the flow of current to said cartridges, means associated with said commutator for normally preventing operation thereof and being arranged to release said commutator when desired to permit operation of the commutator, whereby the circuit to the cartridges is closed, a safety switch mounted within the housing and including a pair of switch blades connected in the circuit between the source of supply and the commutator, an operating member movable within the housing and having a contact adapted to engage the blades to electrically connect the same whereby current is conducted to the commutator, and means carried by the housing for holding the operating member in a position with its contact disengaged from the switch blades during the raising and lowering of the device through the well casing, whereby no current flows to the commutator and cartridges during such movement of the device through the casing and accidental firing of the cartridges is prevented.

14. A perforating device for a well casing including, a housing adapted to be lowered into said casing on a flexible line, gun cartridges mounted in the casing and arranged to be electrically fired to perforate the casing, a source of electrical current supply within the housing, means for electrically connecting the source of current supply to the cartridges, a control means interposed in the circuit between the supply and the cartridges for controlling the flow of current to said cartridges, an operating lever associated with the control means and normally preventing operation thereof, and electrically operated means for actuating the lever, whereby said lever releases the control means to permit the same to operate and close the electrical circuit to the cartridges.

15. A perforating device for a well casing including, a housing adapted to be lowered into said casing on a flexible line, gun cartridges mounted in the casing and arranged to be electrically fired to perforate the casing, a source of electrical current supply within the housing, means for electrically connecting the source of current supply to the cartridges, a control means interposed in the circuit between the supply and the cartridges for controlling the flow of cur-

rent to said cartridges, an operating lever associated with the control means and normally preventing operation thereof, electrically operated means for actuating the lever, whereby said lever releases the control means to permit the same to operate and close the electrical circuit to the cartridges, and means adapted to be dropped from the surface for completing an electrical circuit to said electrically operated means, whereby the cartridges may be fired at a desired time.

16. A perforating device for a well casing including, a housing adapted to be lowered into said casing on a flexible line, gun cartridges mounted in the casing and arranged to be electrically fired to perforate the casing, a source of electrical current supply within the housing, means for electrically connecting the source of current supply to the cartridges, a control means interposed in the circuit between the supply and the cartridges for controlling the flow of current to said cartridges, an operating lever associated with the control means and normally preventing operation thereof, and a solenoid for actuating the lever, whereby said lever releases the control means to permit the same to operate and close the electrical circuit to the cartridges.

17. A perforating device for a well casing including, a housing adapted to be lowered into said casing on a flexible line, gun cartridges mounted in the casing and arranged to be electrically fired to perforate the casing, a source of electrical current supply within the housing, means for electrically connecting the source of current supply to the cartridges, a control means interposed in the circuit between the supply and the cartridges for controlling the flow of current to said cartridges, an operating lever associated with the control means and normally preventing operation thereof, a solenoid for actuating the lever, whereby said lever releases the control means to permit the same to operate and close the electrical circuit to the cartridges, and a safety switch connected in the electrical circuit between the source of current supply and the control means for preventing flow of current to

the control means prior to the positioning of the device in the well casing.

18. A perforating device for a well casing including, a housing adapted to be lowered into said casing, gun cartridges mounted in the casing and arranged to be electrically fired to perforate the well casing, a source of electrical current supply within the housing and connected with the cartridges, whereby said cartridges are fired when the current is conducted thereto, a safety switch mounted within the housing and including a pair of switch blades connected in the electrical circuit between the source of supply and the cartridges, and a movable operating member movable between and arranged to coact with the switch blades to open and close the circuit, and means for releasably maintaining the operating member in a position holding the circuit open during raising and lowering of the device through the casing, whereby no current may flow to the cartridges during such movement of the device.

19. A perforating device for a well casing including, a housing adapted to be lowered into said casing, gun cartridges mounted in the casing and arranged to be electrically fired to perforate the well casing, a source of electrical current supply within the housing and connected with the cartridges, whereby said cartridges are fired when the current is conducted thereto, a safety switch mounted within the housing and including a pair of switch blades connected in the electrical circuit between the source of supply and the cartridges, an operating member movable within the housing relative to said blades and having a contact adapted to engage the blades to electrically connect the same whereby current may flow to the cartridges, and means carried by the housing for holding the operating member in a position with its contact disengaged from the switch blades during raising and lowering of the device through the well casing to prevent a flow of current to the cartridges during such movement.

LEONIDAS C. MILLER.
